ALFRED L. ATHERTON, OF PENN TOWNSHIP, ALLEGHENY COUNTY, PENNSYLVANIA.
ASSIGNOR TO WESTINGHOUSE ELECTRIC & MANUFACTURING COMPANY, A CORPORATION OF PENNSYLVANIA.

LIGHTNING ARRESTER.

Application filed February 7, 1927. Serial No. 166,312.

My invention relates to lightning arresters and especially to new and improved casings for the same.

More particularly, my invention relates to 5 a novel lightning arrester construction which comprises a plurality of unit devices which are arranged to facilitate assembling any number thereof.

An object of my invention is to provide 10 a compact and inexpensive assembly of units which is strong and rigid.

Still another object of my invention is to provide a casing which is particularly adapted to lightning arresters of the autovalve 15 type or any similar type having a plurality of discharge paths.

In the accompanying drawing,

Fig. 1 is a view, partly in elevation and partly in section, of an arrester unit embodying my invention, and

Fig. 2 is a view, in side elevation, of a complete arrester assembly embodying my invention.

A substantially cylindrical casing member 25 3 of porcelain is provided with four cylindrical, parallel, and axially extending perforations or chambers 4 open at both ends. Disposed in each chamber is a stack of discs 5, such as are described in the Slepian Patent 30 No. 1,509,493, issued September 23, 1924.

Disposed in the upper end of each chamber, is a spring 6 for maintaining the discs under a compressional stress. A flexible shunt 7 of good conducting material is provided for by-passing current around the 35 spring.

A base member 8, comprising two substantially circular metallic plates 9 and 10 of different diameters, is secured to the bottom end of the casing member. The smaller plate 9 fits the bottom end of the casing member to retain the discs within the chambers and is provided with eight perforations spaced at equal distances around the circumference thereof. The larger plate 10, or base member proper, is provided with similarly disposed perforations, whereby the two plates may be fastened together, as by means of bolts 11. The plates are so joined that 45 a substantially annular opening 12 is provided therebetween. The purpose of this opening will be hereinafter set forth.

The larger plate 10 has an annular projecting portion 13 disposed parallel to its

vertical axis and arranged to fit over the 55 end of the porcelain casing member 3, thereby providing an annular depression or pocket 14 therebetween. A quantity of Portland cement 15 is disposed in the pocket, thereby securing the base member 8 to the bottom of 60 the casing member 3.

After the larger plate 10 has been cemented to the porcelain casing member 3, a cork gasket 16 is applied to the bottom end of the casing member and is held in place by 65 drawing up the smaller plate 9 toward the larger plate 10.

The cork gasket 16 is compressed to one half of its original thickness, thereby making it substantially impervious to water. It 70 has been found that the cement which secures the base member to the casing member is not sufficiently impervious to keep water from entering the chambers. Therefore, the cork gasket has been provided to 75 accomplish the result mentioned above.

The annular opening 12, disposed between the two plates 9 and 10 that constitute the base member 8, serves as an outlet for any moisture which may enter the annular pocket 80 14 and seep through the cement 15.

The inner surface of the upwardly projecting portion 13 of the base member is corrugated, as shown at 17, to make the adhesion of the cement more perfect. The 85 outer surface of the lower end 18 of the casing member is either sanded or knurled for the same reason.

A metallic, circular cap member 20, having a projecting portion adapted to fit the 90 upper end of the casing member, is mounted thereupon, thereby providing an annular pocket or depression 21. The cap member 20 is cemented to the upper end of the casing member 3, with a cork gasket 22 interposed between the end surface of the casing member and that portion of the cap member adjacent thereto. The gasket 22 is maintained under compression similar to the lower gasket 16, and although it may be injured somewhat during the cementing of the cap, it does not need to be so impervious to water as the lower gasket 16, and it serves the important function of cushioning any irregularities.

A quantity of Portland cement 23 is disposed in the annular pocket 21, completely filling it. The inner surface 24 of the pro-

jecting portion of the cap member is corrugated, and the surface of the end portion 25 of the casing member is sanded or knurled, thereby providing better adhesion between 5 the cement and the members joined by it.

The cap member 20 is provided with a central portion 26 which is slightly elevated and which slopes gradually toward the outer portions of the cap member. This crowning of 10 the top casting, together with the fact that there is no perforation in the same, insures that no moisture can enter into the arrester unit through the top.

The cap and base members are provided 15 with like thickened portions or pads 26^a and 27, respectively, which are easily machined to provide a level surface, and which provide a space for the exit of water, in case any water should seep through the cement 20 15. The pads 26^a and 27 are perforated, as indicated at 28, to provide means for mounting the base member of one unit upon the cap member of another unit and fastening them together by means of bolts 29, as shown 25 in Fig. 2.

The casing member 3 is provided with a downwardly and outwardly projecting skirt-like portion 30. This portion provides an increase in the creepage distance between the 30 cap and base members. In addition, this portion provides a protection against moisture entering the chambers by way of the annular pocket 14.

Referring to Fig. 2, a complete lightning- 35 arrester assembly is shown comprising eight of the unit discharge devices described above. The said devices are mounted serially in a column, one upon the other, and fastened together by the bolts 29 projecting 40 through the similarly disposed openings 28 in adjacent caps 20 and bases 8. The lower end of the column of unit discharge devices is mounted upon a base 32 which is electrically connected to the ground. The upper 45 end of the column is provided with a spark-gap electrode 33. A line-potential spark-gap electrode 34 is disposed at a distance from the first electrode and both are protected by a canopy or hood 35 resting, at 50 one end, on the top of the lightning-arrester column.

The line-potential electrode 34 is mounted upon a frame-work structure 36 and insulated from the ground and from the hood by 55 means of superpositioned insulators 37 and 38, respectively. The line conductor 39, leading to the line which the lightning arrester is to protect, is mounted upon the frame-work 36 at a point between the said insulators 37 and 38.

It is apparent that the type of unit-casing construction herein described is particularly adapted to a lightning arrester of the autovalve type or of any similar type which 60 comprises a plurality of unit discharge de-

vices mounted one upon another. By my invention, I am able to mount a plurality of these unit discharge devices in a column which will be strong and rigid, without sacrificing the ease with which they may be 70 assembled.

My invention provides a means for assembling a plurality of unit discharge devices which does not involve disposing fastening members of a conducting material within the 75 porcelain casings, my fastening members 29 being disposed outside of the casings 3. This feature is particularly desirable, since I am able to obtain greater insulating qualities in smaller casings than heretofore. 80

Heretofore, difficulty has been experienced in joining a plurality of unit discharge devices, owing to the fact that the brittle character of the porcelain constituting the casings was a serious detriment to 85 the mechanical strength of a column of such devices. My invention, utilizing all-metal joints, provides a column having greater strength at the points at which unit discharge devices are joined. 90

Another important feature of my invention is the elimination of all insulating materials except porcelain. This will be recognized as a particular advantage because of the qualities of its long life, its ability to 95 permanently withstand weather changes in temperature, and its imperviousness to moisture, which are superior to the characteristics of such fibrous insulating members as micarta tubes and wooden supporting rods 100 which are standard parts in other high-voltage arresters on the market.

Although I have described herein a particular embodiment of my invention, I do not wish to be altogether limited to any 105 such specific structure, and I desire that the appended claims shall be accorded the broadest interpretation consistent with their wording and the prior art.

I claim as my invention:

1. A unit discharge device comprising a tubular casing member having a plurality of chambers, discharging means disposed therein, a base member having an annular flange portion arranged to telescope the end of the casing member thereby closing one set of ends of the chambers, a quantity of cement disposed between the telescoping portions of the casing member and the base member thereby securing the base member to the casing member, a gasket interposed between the end surface of the casing and the face plate of the base adjacent thereto, thereby preventing moisture from entering the chambers, said base member having also an opening therethrough arranged to permit any moisture which permeates the cement to flow out. 115

2. A unit discharge device comprising a casing member having a plurality of dis- 120

charge paths therethrough, a cap member therethrough, said annular opening constituting a means of draining any moisture which collects between the annular flange portion and the end of the casing adjacent thereto.

5 charge paths therethrough, a cap member therethrough, said annular opening constituting a means of draining any moisture which collects between the annular flange portion and the end of the casing adjacent thereto.

Having an annular flange portion arranged to fit over the upper end of the casing member, said cap member having an elevated central portion, a base member comprising a plurality of members fastened together having an annular flange arranged to fit over the lower end of the casing, said base also having a substantially annular opening

In testimony whereof, I have hereunto 15
subscribed my name this 5th day of Febru-
ary, 1927.

ALFRED L. ATHERTON.
